[57] **CLAIM**

The ornamental design for a peg lock, as shown and described.

DESCRIPTION

FIG. 1 is a perspective view of a peg lock showing my new design, with a plurality of items supported on a display peg in broken line for illustrative purposes only and forming no part of the claimed design;

FIG. 2 is a top plan view of the peg lock;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.
